UNITED STATES PATENT OFFICE.

JOHN GIBBONS, OF WEST TROY, NEW YORK, ASSIGNOR TO THE MENEELY HARDWARE COMPANY, OF SAME PLACE.

OILER FOR CAR-AXLES.

SPECIFICATION forming part of Letters Patent No. 311,071, dated January 20, 1885.

Application filed June 18, 1884. (No model.)

To all whom it may concern:

Be it known that I, JOHN GIBBONS, of the village of West Troy, county of Albany, State of New York, have invented a new and useful Improvement in Oilers for Car-Axles, of which the following is a specification.

My invention relates to that class of devices which are used in connection with car-axles to supply lubricating material thereto; and the object and purpose of my invention is to improve that class of devices by making them more efficient in their operation, and to render them more economical in the use of lubricating material.

My invention consists, as will be more fully detailed hereinafter in connection with its illustration, in the combination of two separate oil-receptacles for each journal-box, each being constructed to contain oil, and provided with a wick-holder and wick, and the two receptacles for oil and a wick connected at the bottom of each to the other by means of springs which force inwardly toward each other the tops of the receptacles, so as to keep the projecting wicks in contact with and against the intermediately-placed axle.

Accompanying this specification, to form a part of it, there are three plates of drawings containing five figures, illustrating my invention, with the same designation of its parts by letter-reference used in all of them.

Of these illustrations, Figure 1 shows a perspective of the two oil-receptacles, they being shown as spread apart against the force of the springs which connect them at the bottom, their position when drawn in toward each other at the top being indicated by a dotted line. Fig. 2 shows a combined longitudinal section and side elevation of a car-axle box, with my improved oiler applied thereto. Fig. 3 shows a cross-section of a car-axle box containing my invention. Fig. 4 shows as detached from the device one of my improved wick-holders, and Fig. 5 illustrates a detached wick and wick-holder.

The several parts of the mechanism constituting my invention and the parts of a car-axle box with which it connects are designated by letters of reference, and their function is described as follows:

The letters R R indicate two oil holders or

receptacles, which at the bottom, near the ends, are connected by two springs, S S, the elastic force of which springs is exerted to force in toward each other the tops of the two receptacles or holders, as indicated by the dotted line d. These holders or vessels are made to fit into the ordinary car-axle boxes for convenience of application, although their form may be varied, provided the relative arrangement and construction of the parts as to function are retained.

The letters O indicate wick-openings made in the vessels or receptacles, and the letters N indicate cross-recesses made in the two vessels in opposite positions, for the reception of the axle-collar.

The letters H designate wick-holders, and W wicks, that are supported in position by said wick-holders. These wick-holders consist of a plate that is curved to coincide with the concavity of the inner faces of the two vessels oppositely to where the said holders and wicks are placed.

The letters W designate wicks of which there is one for each vessel. The said wick-holders are placed between two thicknesses of the wick by folding the latter centrally cross-wise with the cut ends of the wick within the vessel and the fold-line of the wick on the projecting holder, with the latter passed through the opening O.

The letters a a designate openings in the vessels, for filling them with oil or lubricating material. The vessels or receptacles are designated at R, and they are each made of two parts or lobes, that one designated at D' being designed by its form to occupy a position at the side of and below the axle, and that at D'', being connected interiorly with the part D', is made to subtend the outer end of the car-axle, the axle end subtension of the parts D'' of each vessel being directed inwardly and toward each other.

The letters d² designate covers that are pivoted to the tops of the vessels R, as indicated at p, and these covers are adapted to be moved around to close the openings a.

The letter I designates the journal-box; A, the bearing; C, the axle-collar; J, the journal-box cover; P, the pedestal; P', the pedestal-jaw; K, the journal-bearing key, the said parts

being the usual and ordinary parts used in connection with car-axle boxes.

- The operation of my invention, as applied to the foregoing parts of an axle-box, is as follows: The oil vessels or receptacles being supplied with oil through the openings *a*, the wicks are placed on the wick-holders *H*, as shown at Fig. 5, and then inserted in the vessels through the openings *O*, with the top of the wick-holders and wicks projecting therefrom, as shown at Fig. 1. The vessels are then inserted in the journal-box *I*, and put in the position shown at Figs. 2 and 3. Thus placed the wicks absorb oil and convey it by contact to the surface of the axle at each side as it revolves, and with which the wicks are kept in contact by the combined action of the springs *S* and the wick-holders *H*. When oil is put in the journal-box proper, for distribution to the axles by means of wicks or waste, the oil is thrown about by the motion of the trucks, and is thus made to drip therefrom onto the track and surroundings, which is objectionable.
- By using vessels to contain the oil for lubricating the axle, with said vessels inserted within the journal-box, instead of employing the journal-box to contain the oil, the spilling and consequent dripping of the oil is prevented.
- Experience shows that a small quantity of oil regularly applied answers as good a purpose for lubrication as a superfluity of it. Where the proper quantity of oil is used there is economy, and where a superfluity of it is employed there is consequent waste; and to meet these better conditions of use is one of the objects of my invention.

Another useful feature of my invention is that it can be applied to the ordinary construction of journal-box, to which no change of the surrounding parts is required, and it can be easily removed from the journal-box.

While I have shown and described a peculiar form of vessel for containing lubricating material, I do not desire to limit my invention to

the precise form shown; but I do limit it to a construction in which the same functions shall be produced by form and in relatively the same or substantially the same manner.

Having thus described my invention, what I claim, and desire to secure by Letters Patent, is—

1. The combination, with the journal-box *I*, of the vessels *R* *R*, constructed with openings *a* and wick-openings *O*, and adapted to be inserted within said journal-box, substantially in the manner as and for the purposes set forth. 55
2. In an oiler for a car-axle, the combination of the vessels *R*, adapted to be inserted within a car journal-box, as shown, the springs *S*, connecting the said vessels, the wick-holders *H*, and the wicks *W*, the said parts being constructed and arranged to operate substantially in the manner as and for the purposes set forth. 60
3. In an oiler for a car-axle, the combination of the vessels *R*, made with the opposite recesses, *N*, the springs *S* *S*, connecting said vessels, the wick-holders *H*, and the wicks *W*, the said parts being constructed and arranged to operate substantially in the manner as and for the purposes set forth. 65
4. In an oiler for a car-axle, the combination of the vessels *R*, made with the anterior lobe *D*², the posterior lobe *D'*, and the wick-openings *O*, as shown and described. 70
5. The combination, with the journal-box *I*, of the vessels *R*, constructed with the openings *a*, covers *d*², wick-openings *O*, the springs *S*, the wick-holders *H*, made with the lips *m*, and the wicks *W*, the said parts being constructed and arranged to operate substantially in the manner as and for the purposes set forth. 75

Signed at Troy, N. Y., this 2d day of June, 1884, and in the presence of the two witnesses whose names were by them hereto written.

JOHN GIBBONS.
